(57) **CLAIM**

The ornamental design for a can holder for a can manufacturing apparatus, as shown and described.

DESCRIPTION

FIG. 1 is a perspective view from the front and top side of a can holder for a can manufacturing apparatus.

FIG. 2 is a perspective view from the rear and bottom side thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is a bottom plan view thereof; and,

FIG. 9 is a cross-sectional view taken along the line 9-9 in FIG. 3.

1 Claim, 9 Drawing Sheets
